(No Model.)

C. F. HARTMAN.

RAIL JOINT.

No. 292,223.

Patented Jan. 22, 1884.

UNITED STATES PATENT OFFICE.

CHARLES F. HARTMAN, OF KELLER'S CHURCH, PENNSYLVANIA.

RAIL-JOINT.

SPECIFICATION forming part of Letters Patent No. 292,223, dated January 22, 1884.

Application filed April 26, 1883. (No model.)

To all whom it may concern:

Be it known that I, CHARLES F. HARTMAN, of Keller's Church, county of Bucks, and State of Pennsylvania, have invented an Improvement in Rail-Joints, of which the following is a specification.

My invention has reference to rail-joints, but more particularly to an improvement upon Letters Patent granted to me March 27, A. D. 10 1883, and numbered 274,593; and it consists in clamps of peculiar construction when arranged with a suitable chair adapted to hold the two ends of the rails and limit their longitudinal movement, one of said clamps or clamping-bolts being arranged over the joint, and in many details of construction, all of which is 15 fully set forth in the following specification and shown in the accompanying drawings, which form part thereof.

20 The object of my invention is to make a simple, cheap, and strong rail-joint, adapted to take the place of the loose fish-plates now in use.

In the drawings, Figure 1 is a plan view of 25 my improved rail-joint, with a small portion broken out. Fig. 2 is a side elevation of same, and Fig. 3 is a cross-section of same on line *xx*.

A are the ends of two adjacent rails. They rest upon a chair, B, provided on one 30 side with the curved flange C, which fits up around the lower part of the rails, terminating just below the head, as shown. This flange C may be the full length of the chair B. The chair B is perforated in three or more 35 places, C', the perforations being preferably rectangular in sectional area, and are arranged at right angles to the rails A, and are adapted to receive the peculiarly-shaped clamps or bolts D, having the threaded ends F and the 40 curved ends E, similarly shaped to the part or flange C of the chair previously described. These curved parts C and E are somewhat varied, to suit the cross-section of the rail used; but in all cases they are approximately of the 45 shape shown in Fig. 3. The clamps D are tightened by nuts G, which, when screwed up tight, are prevented from turning by a key, H, made wedge shape, which are driven through slots *f* in the ends F. I do not limit 50 myself to this particular manner of preventing unscrewing of the nuts, as a double or lock nut might be used, or any of the well-known

devices now in the market. One of these clamps, D, and its curved end E fit over the juncture of the two rail ends A, as shown in 55 Fig. 1, and this is practically insured by lugs J, cast in the chair or carriage B on either side of the center, which fit the slots or notches A', near the ends of the bottom flange or foot of the rails A, as clearly shown in Fig. 1, the said slots and lugs preventing the rails, when laid on grades, from working out of the 60 chairs. The chair B is provided with flanges I, notched, as at *i*, for the spikes, by which it is secured to the ties, the said flanges running 65 parallel with the rails, and also with a re-enforcing band, K, of metal, cast to it below the middle clamping-bolt, to give additional strength when the chair is laid between the railroad-ties, or when its ends simply rest upon 70 them.

I do not claim the lugs, notches, and re-enforcements specifically, for each is old in itself, and therefore limit myself to their use when combined with other features and elements, as set forth in the foregoing specification and appended claims. 75

Having now described my invention, what I claim as new, and desire to secure by Letters Patent, is—

1. In a rail-joint, a chair upon which the adjacent ends of two rails rest, provided with a clamping-flange shaped to conform to the rail, as shown, in combination with clamps or clamping-bolts, which are held and guided 80 by said chair, and having their ends curved, to conform also to the shape of the rail, the rail ends being firmly clamped between said flange and clamping-bolts, substantially as shown, and means to prevent said rail ends 85 being drawn out of the chair, substantially as and for the purpose specified.

2. In a rail-joint, a chair upon which the adjacent ends of two rails rest, provided with a clamping-flange and retaining-lugs, in combination with the rails having slots near their 90 ends, and clamping-bolts, the ends of said bolts and flange being shaped to conform to the sides of the rail, as shown, one of said clamping-bolts being arranged over the juncture of the two 95 rail ends, substantially as and for the purpose specified.

3. In a rail-joint, the chair B, provided with lugs J, flange C, extending up to the head of

the rail, and transverse apertures C', in combination with rail ends A, having slots A' near their ends, bolts D, having curved ends E, and nuts G, substantially as and for the purpose specified.

4. In a rail-joint, the chair B, provided with lugs J J, clamping-flange C, extending up to the rail head, and fitting the side of the rail, and transverse apertures or holes C', in combination with rail ends A, having slots A' near their ends, clamping-bolts D, having threaded ends F and curved ends E, to fit the side of the rails, a nut, G, and means to lock said nut in position when the rails are clamped, substantially as and for the purpose specified.

5. In a rail-joint, the chair B, provided with clamping-flange C, re-enforcing band K, lugs J J, and transverse holes C', in combination with rails A, having slots A' in their bottom flanges near their ends, bolts D, having curved ends E, and means to cause the rail to be clamped between said ends E and flange C, substantially as and for the purpose specified.

In testimony of which invention I hereunto set my hand.

CHARLES F. HARTMAN.
